UNITED STATES PATENT OFFICE.

ROBERT B. HUTCHISON, OF WILKINSBURG, PENNSYLVANIA.

SURFACE-CLEANING MACHINE.

No. 813,557.

Specification of Letters Patent.

Patented Feb. 27, 1906.

Application filed July 27, 1904. Serial No. 218,330.

To all whom it may concern:

Be it known that I, ROBERT B. HUTCHISON, a citizen of the United States, residing at Wilkinsburg, in the county of Allegheny and State of Pennsylvania, have invented 5 certain new and useful Improvements in Surface-Cleaning Machines, of which the following is a specification, reference being had therein to the accompanying drawings, forming part of this specification, in which—

Figure 1 is a plan view, a portion of the handle-bar being removed. Fig. 2 is a vertical longitudinal section through the cover on the line II II of Fig. 4. Fig. 3 is a side elevation. Fig. 4 is a cross-section on the line IV IV of Fig. 3. Fig. 5 is a plan view of the apparatus with the cover removed. Fig. 6 is an end view. Fig. 7 is a detail of the frame, showing the wheel supporting and adjusting 20 slot. Fig. 8 is a detail view of one of the knockers. Fig. 9 is a vertical cross-section on the line IX IX of Fig. 5 without the pan.

My invention refers to improvements in power-actuated surface-cleaning machines 25 for the purpose of cleaning carpets, floors, or wherever it is desirable to remove an accumulation of dirt or dust or to renew the original freshness of color of the surface.

The apparatus comprising the invention is 30 particularly adapted to cleaning carpets or rugs on the floor without removal, and is designed to be moved around over the floor by the operator and to be actuated by a motor constituting a portion of the mechanism by 35 which the active elements of the device are driven.

The apparatus consists of a supporting-frame mounted on rollers or wheels, with a power-driven rotary brush provided with 40 knockers, a motor, and a surrounding inclosing dust-casing.

Referring to the drawings, 22 are flat side bars constituting the main portions of the frame of the apparatus, said bars being located vertically edgewise and provided with cross-bars 3 at each end by which the frame is strengthened, upon which frame the wheels, motor, rotating brush, and handle are mounted.

4 represents the wheels, preferably rubber-tired, mounted on bearing-studs which are vertically adjustable in slots 5 and secured by nuts 6, by which the frame and its sup-

ported rotating brush are adjusted with relation to the floor-surface. 55

7 is the brush-shaft, rotatably mounted in suitable bearings in the cross-bars at each end and provided with a series of spirally-arranged bristles 8, extending from the shaft for its full length, with intervening correspondingly spirally arranged openings, as clearly shown. The shaft as thus provided with bristles constitutes a cylindrical brush adapted to make brushing contact with a floor or carpet surface, so as to dislodge and 65 remove the dust, &c., as will be readily understood. The brush-shaft 7 is provided with several beaters, consisting of small metallic or rubber balls 10, flexibly connected with the shaft in any suitable manner, as by a link 10^a 70 and an intervening spiral spring 11. In the rapid rotation of the shaft as the machine is moved around over the floor these beaters come into rapid contact with the carpet, thoroughly dislodging the dust, &c., which is 75 then taken up and removed by the brushes.

12 is a motor, preferably an electric motor, rigidly mounted upon the frame and provided with the usual driving-pinion 13, in engagement with a toothed wheel 14, mounted 80 on one end of the brush-shaft, as shown, by which construction rapid rotary motion is imparted to the brush. For the purpose of reducing noise, rawhide or fiber gearing may be used to transmit power from the motor to the 85 brush.

The frame of the machine is provided with a handle-bar 15, having handles at its upper end and rigidly secured to the frame at the base in any suitable manner, as by bolts, by 90 which construction the machine is moved around over the floor upon its supporting-wheels. Power is supplied to the motor by conducting-wires 16, connected with binding-posts on the motor, said wires being of 95 suitable length and furnished with a socket or other electrical connecting device 17, adapted to be inserted in an ordinary electric-lamp-socket or connected with other source of current, by which means the motor is supplied at whatever position it may be in the room. By making these wires of sufficient length the machine may be moved around over the entire floor with ease and the supply maintained very conveniently. I do not, 100 however, desire to be confined to the use of 105

an electric motor, as it is obvious that any other suitable kind of driving mechanism may be employed which may be mounted upon the machine.

5 At each end of the frame are rigidly-located end plates 18, of sheet metal, while the entire brush is inclosed within a removable casing 19, provided with a handle 20, having downwardly-turned sides and terminating in 10 inwardly-extending bottom portions 21, having backwardly and upwardly extending dust-retaining flanges or lips 22. The bottom portions, constituting the lower inclosing walls of the pan, are preferably sloped inwardly and downwardly and then somewhat upwardly, as shown in Fig. 4, thus providing obtuse ridges 23, adapted to bear at all times upon the floor or carpet surface. The entire casing fits over the brush and in engagement 15 with the end plates 18, for which purpose the casing is provided with rectangular openings at each end, across which the end plates extend when the casing is in place, lapping over the ends of the casing sufficiently far to make 20 a practically dust-tight joint. Sufficient vertical play is provided above the bars 2, as indicated at 24, this allowing the casing to rise and fall with relation to the frame and end plates, it being understood that the casing at 25 all times rests by gravity upon the floor and is carried forwardly or backwardly by its lateral engagement with the bars 2. By this means the casing will adjust itself to the carpet independent of the frame, thus insuring 30 contact with the surface in case of carpets of different textures or length of pile, while accommodating itself to unevennesses in the surface.

When thus constructed and assembled, 40 power having been supplied to the motor, the brushes are rotated and together with their coöperating beaters rapidly remove the dust. Such operation is greatly facilitated by the spiral arrangement of the brushes, which tend 45 to move the dust lengthwise of the brush as well as upwardly from the floor, finally depositing it in the pan at each side, where it is accumulated and may be removed from time to time, as will be readily understood, by 50 merely lifting the casing upwardly and inverting it.

The machine may also be used upon vertical walls as well as horizontal and on different surfaces—as, for instance, for renewing 55 the brick or stone surfaces on old buildings. The invention may be used for the purpose of cleaning the paint off of any surface by friction.

The manipulation of the machine requires no special skill, its work is very thorough and 60 rapid, and it accomplishes at low cost and with great facility a large amount of heretofore laborious and expensive work.

Various changes or modifications may be

made in the design, proportions, or other details of the invention by the skilled mechanic; 65 but all such changes are to be considered as within the scope of the following claims.

What I claim is—

1. In a surface-cleaning machine, the combination of a framework composed of two 70 main bars arranged parallel to each other, cross-bars providing bearings, a rotatable brush journaled in said bearings, supplemental extensions at each end provided with vertically-adjustable supporting-wheels, a motor, connecting-gearing arranged to transmit motion from the motor to the brush, and a removable casing provided with openings arranged to engage the frame and to be vertically movable relatively thereto, said casing 75 being adapted to normally rest upon the floor and having inwardly and upwardly turned bottom portions adapted to collect the products of the brushing operation, substantially as set forth. 85

2. In a surface-cleaning machine, the combination of a framework composed of two main bars arranged parallel to each other and cross-bars providing bearings, a rotatable brush journaled in said bearings, supplemental extensions at each end provided with vertically-adjustable supporting-wheels, a motor, connecting-gearing arranged to transmit motion from the motor to the brush, and a removable casing provided with openings arranged to engage the frame and to be vertically movable relatively thereto, said casing 90 being adapted to normally rest upon the floor and having inwardly and upwardly turned bottom portions adapted to collect the products of the brushing operation, said frame 95 being provided with plates in position to cover the openings in the casing, substantially as set forth. 100

3. In a surface-cleaning machine, the combination of a portable frame having adjustable supporting-wheels, a rotatable cleaning-brush mounted in said frame, a motor mounted on the frame and in driving engagement with said brush, means for supplying power 105 to said motor, a removable casing for the brush freely mounted upon said framework adapted to rest upon the floor independent of the frame and to permit of relatively independent vertical movement of said frame, 110 said casing being provided with clearance-openings for the frame and having inwardly and upwardly turned bottom portions comprising oppositely-arranged pans adapted to collect the products of the brushing operation, 115 with plates engaging the brush-shaft and frame at each end overlapping the casing to close the openings therein, substantially as set forth. 120

4. In a surface-cleaning machine, the combination with a rotatable brush, of a heating 125

device flexibly connected with the shaft of the brush, and an intervening resilient stiffening device, substantially as set forth.

5. In a surface-cleaning machine, the combination with a rotatable brush, of a beating device flexibly connected with the shaft of the brush, and an intervening spiral spring arranged to normally hold the beating device

outwardly beyond the shaft, substantially as set forth. 10

In testimony whereof I affix my signature in presence of two witnesses.

ROBERT B. HUTCHISON.
